(57) CLAIM

I claim the ornamental design for a shoe outsole, as shown and described.

DESCRIPTION

FIG. 1 is a bottom view of the shoe outsole;

FIG. 2 is a left side view of the shoe outsole;

FIG. 3 is a right side view of the shoe outsole;

FIG. 4 is a front view of the shoe outsole; and,

FIG. 5 is a rear view of the shoe outsole.

The broken lines in the FIGURES showing the remainder of the shoe are for illustrative purposes only and form no part of the claimed design.
